UNITED STATES PATENT OFFICE.

GEORGE P. BUTLER, OF LEBANON, NEW HAMPSHIRE.

SIGN-POST.

1,275,125.

Specification of Letters Patent.

Patented Aug. 6, 1918.

Application filed July 20, 1917. Serial No. 181,724.

To all whom it may concern:

Be it known that I, GEORGE P. BUTLER, a citizen of the United States, residing at Lebanon, in the county of Grafton and State 5 of New Hampshire, have invented a new and useful Improvement in Sign-Posts; and I do hereby declare the following, when taken in connection with the accompanying drawings and the characters of reference 10 marked thereon, to be a full, clear, and exact description of the same, and which said drawings constitute part of this application, and represent, in—

Figure 1 a face view of a sign-post constructed in accordance with my invention.

Fig. 2 a broken face view of the central portion of the upper edge of the lower sign-board and the lower edge of the upper sign-board.

Fig. 3 a plan view partly in section of the pair of clamping-collars employed in connecting the upper and lower sign-boards.

Fig. 4 an edge view of one of the collars.

Fig. 5 a broken face view of a portion of 25 the sign-board illustrating the application of a sign-wing attached thereto.

Fig. 6 a face view of the sign-wing detached.

Fig. 7 a sectional view on the line 7—7 30 of Fig. 5.

Fig. 8 a sectional view on the line 8—8 of Fig. 5.

This invention relates to an improvement in sign posts, and particularly to sign posts 35 made from metal and with especial reference to sign posts which consist of a lower sign board and an upper sign board arranged at angles to each other, the object of the invention being a construction which permits 40 of the boards to be adjusted at the desired angle and firmly secured in place, and also to provide for the attachment of a lantern to a sign post, and also for the application thereto of so called sign-wings; and the invention 45 consists in the construction herein-after described and particularly recited in the claims.

In carrying out my invention I employ a sign-board 9 which I will term the lower 50 sign-board which is mounted in the upper end of a sign-post 10 being provided with a shank 11 which may be set into a socket 12 on the top of the post, and if the shank is round will be secured in the socket by a screw 13, or the shank may be made angular and set into an angular hole in the post

as indicated in Fig. 8 of the drawings. On the top of the board and centrally arranged with respect thereto, is a plate 14 flat on its upper face and having beveled under edges. 60 The upper sign-board 15 has a corresponding plate 16 in the center of its lower edge, these plates adapted to rest one upon the other and are connected together by two semi-circular clamping collars 17 and 18, 65 these sections being formed with V-shaped grooves 19 so that the collars fit over the plates and the collars are connected together by screws 20 so as to firmly connect the upper sign-board with the lower sign board 70 and permit the boards to be adjusted to any desired angle with respect to each other.

Preferably and as herein shown, the upper sign-board 15 will be provided with a plate 21 similar to the plate 14 on the lower 75 sign-board upon which may rest the base 22 of a lantern 23, this lantern being secured to the plate 21 by collars 24 like the collars 17 and 18 just described. If the upper sign-board is not used a lantern may be placed 80 upon the plate 14 upon the top of the lower sign-board. At some cross-roads it is necessary to have what is called a sign wing in which case I employ a sign-wing 25 formed at its inner end with a disk 26 85 adapted to rest upon the top of the socket 12 on the sign-post, the disk being provided with a hole 27 for the passage through it of the shank 11. When the sign-wing is to be used an annular rib 28 from the lower 90 end of the socket 12 will be provided with notches 29 to receive the lower corner 30 of the sign-wing plate so that the inner end of the sign-wing plate will be firmly supported by the socket. It will thus be seen that I 95 provide for sign-boards which may be arranged at an angle to each other according to the direction of the roads where they are placed, and also provide for additional sign-wings if such are necessary at any particular junction. 100

I claim:—

1. In a device of the character described, a sign board provided at its upper end with a plate having a flat upper face and a beveled under face, and means for clamping a device having a flat under face to the said plate, whereby the device may be mounted upon the sign board at any desired angle. 105

2. In a device of the character described, 110 a sign board provided at its upper end with a plate having a flat upper face and a bev-

eled under face, and means for clamping a device having a flat under face to the said plate, said means comprising two semi-circular collars the inner faces of which have 5 V-shaped grooves, whereby said device may be mounted upon the sign board at any desired angle.

3. A plurality of angularly adjustable sign-boards provided with adjacent plates 10 having flat opposing surfaces with beveled

edges with means for embracing said edges and clamping said boards together and angularly adjusting same.

In testimony whereof, I have signed this specification in the presence of two sub- 15 scribing witnesses.

GEO. P. BUTLER.
